(57) **CLAIM**

I claim the ornamental design for a reconfigurable astronomical model, as shown and described.

DESCRIPTION

FIG. 1 is a perspective view of a reconfigurable astronomical model embodying my new design;

FIG. 2 is a top plan view thereof;

FIG. 3 is a perspective view, similar to FIG. 1, but with all of the astronomical objects vertically aligned with one another;

FIG. 4 is a front elevational view of FIG. 3;

FIG. 5 is a right side elevational view of FIG. 3, the left side elevational view being a mirror image thereof; and,

FIG. 6 is a top plan view of FIG. 3.

1 Claim, 6 Drawing Sheets(56)
